[57] CLAIM

The ornamental design for a mailbox and sign post, as shown and described.

DESCRIPTION

FIG. 1 is a side elevational view of a mailbox and sign post showing my new design, it being understood that the opposite side view is a mirror image thereof;

FIG. 2 is a front elevational view thereof;

FIG. 3 is a rear elevational view thereof;

FIG. 4 is a top plan view thereof;

FIG. 5 is an enlarged view of the end of the horizontal cross bar thereof; and,

FIG. 6 is an enlarged view of the uppermost portion of the mailbox and sign post.
